JOURNAL

Charles Edward Hermann, St. Louis, Mo.

Application March 11, 1932, Serial No. 598,218

4 Claims. (Cl. 308—170)

This invention relates to new and useful improvements in oil journals for roller mills. In this type of mill a vertically disposed revoluble spider or support has pivotally suspended therefrom a plurality of journals spaced equidistant about the axis of rotation. The lower end of each journal carries a revoluble roller which when the mill is in actuation is moved by centrifugal action against and operates over the inner face of a grinding ring so that the material contained in the mill chamber is ground by the action of the rollers against said ring. As the rollers operate at high speed in a chamber which is full of finely ground abrasive material and as the journal is subjected to a great deal of strain on account of the blows received from striking large pieces of rock or other material contained in the chamber, it is obvious that the journal should have ample and efficient lubrication, that it should have large bearing surfaces and be of sturdy construction, and that it be dust-proof to protect the bearings and at the same time prevent grease and oil from escaping from the journal into the grinding chamber.

The objects of the present invention are to provide a journal which is efficiently lubricated and has large oil capacity, which is of sturdy construction and is adjustable to provide for wear of the wearing surfaces and which is sealed so as to prevent dust from entering the journal and also seal the grease and oil therein.

Other objects of the invention are to provide a journal for pulverizing machines having a stationarily mounted shaft and having a revoluble lower casing carried by said shaft and carrying the roller, the lower end of said casing forming an oil reservoir and said shaft and said casing being provided with oil passageways whereby oil is forcibly supplied to the principal bearing surfaces.

Still other objects of the invention are to provide a journal having a two-part casing and a shaft arranged therein, the upper casing being pivotally suspended and having said shaft adjustably secured thereto and the lower casing being revolubly mounted on the lower half of said shaft and carrying at its lower end the pulverizing roller, said revoluble casing forming a dust and grease seal with said shaft and with said upper casing.

Further objects of the invention are to provide a journal comprising an upper casing member adapted to be pivotally suspended from the mill spider, a shaft fixed in said casing member and extending downwardly therefrom, a revolu-

ble casing member revolubly supported on said shaft and having a dust and oil seal therewith and with said upper casing, a roller non-rotatably mounted on the lower end of said revoluble casing, and means for adjusting said shaft in said upper casing axially to take up the wear of the wearing pieces of said shaft and said revoluble casing.

Still further objects of the invention are to provide a journal comprising an upper casing adapted to be pivotally suspended from the mill spider, a shaft adjustably fixed in said upper casing and extending therebelow, a revoluble casing revolubly mounted on the lower half of said shaft and having its lower end extending below said shaft and forming an oil reservoir, and oil passageways formed in said shaft and in said revoluble casing for forcing the oil from said reservoir upwardly and discharging it above the major points of engagement of said shaft with said revoluble casing, whereby oil is caused to circulate from said reservoir to the principal bearing surfaces and returns by gravity to said reservoir.

Still further objects of the invention are to provide in a journal of the class described a shaft having its upper end screw-seated in the upper end of the pivotally suspended casing and adjustable longitudinally thereof, and means for engaging the upper end of said shaft and locking it against rotation.

Additional objects of the invention are to provide a journal for pulverizing mills which is of strong construction, can be readily adjusted to take up wear on the bearings, has large oil capacity and means for recirculating the oil past said bearings and is so constructed that it can be readily assembled and disassembled.

With these and other objects in view, my invention consists in certain novel features of construction and arrangement of parts, hereinafter more fully described and claimed, and illustrated in the accompanying drawings, in which—

Figure 1 is a vertical cross section through my improved journal, taken on line 1—1 of Figure 5.

Figure 2 is a top plan view, partly in cross section, of the upper end thereof.

Figure 3 is a horizontal cross section taken on line 3—3 of Figure 1.

Figure 4 is a horizontal cross section taken on line 4—4 of Figure 1.

Figure 5 is a horizontal cross section taken on line 5—5 of Figure 1.

110

Figure 6 is a vertical cross section taken on line 6—6 of Figure 5.

Figure 7 is a detail cross section of the upper end of the journal showing modified adjusting 5 means.

Figure 8 is a top plan view of same, partly in cross section.

Referring by numerals to the accompanying drawings, 10 indicates a horizontally disposed 10 trunnion shaft on which is arranged the horizontally disposed tubular extension 11 of casing 12. This extension which is formed integral with said casing is arranged to one side thereof and is non-rotatably fixed to said trunnion shaft 15 by a pin 14. The ends of said trunnion shaft are revolvably mounted in suitable bearings formed in the ends of a spider (not shown) so that said casing member 12 and parts associated therewith are pivotally suspended from said 20 spider. The upper end of casing member 12 is internally threaded as shown at 15 and screw-seated therein is the threaded upper end 16 of a shaft 17. The upper end of shaft 17 is formed with an extension 18 which is non-circular in 25 cross section, preferably hexagonal, and extends beyond the upper end of casing member 12. A cap 19 is provided with an inner chamber 20 which is of the same cross sectional contour as head 18 and fits thereover. This cap is provided 30 with a flange 21 having suitable apertures 22 for receiving bolts 23 which latter are screw-seated in the upper end of member 12 and hold said cap 19 in fixed position on said member, thereby locking the shaft 17 against rotative 35 movement. These apertures 22 are preferably formed elongated and arcuate to permit slight turning or adjusting movement of the cap to fit the non-circular head 18.

The lower end of shaft 17 extends a suitable 40 distance below casing member 12 and is provided with a collar 17a preferably formed integral therewith a suitable distance from the lower end 17b. A bearing ring or wearing piece 24 is fixed to the upper face of collar 17a by a plurality 45 of pins 25, and a bearing ring or wearing piece 26 rests on the first ring and is fixed by screws 27 to the lower revolvable casing 28.

The upper casing member 12 and shaft 17 are stationary and the lower casing member 28 is 50 revolvably mounted on said shaft by means of collar 17a and rings 24 and 26.

The lower or revolvable casing 28 consists of two sections 29 and 30, the abutting ends of 55 which are provided, respectively, with flanges 31 and 32. These flanges are formed with coinciding apertures in which are received bolts 34. Nuts 35 are screw-seated on the ends of said 60 bolts and draw said flanges together.

Each nut 35 is locked in position by a cotter 65 pin 36.

The peripheral face of the lower section 30 is tapered downwardly and receives a roller 37 which is held thereon in non-rotative engagement therewith by a key 38. The object of forming the lower section tapered is to permit use of 65 rollers of various thickness and at the same time hold them in proper position without the use of shoulders.

The lower end of section 30 is provided with 70 an extension 39 which is externally threaded and receives a nut 40. This nut bears against the underside of the roller and locks it against downward movement. One side of the nut is split 75 horizontally, as indicated at 41, and a set screw 42 is screw-seated in the lower half and bears

against the upper half, thereby slightly distorting said portions and locking said nut against accidental movement.

A bushing 44 is placed in the bore 45 formed in the section 30 and forms a bearing for the lower portion of shaft 17. The upper end of this bushing is flanged, as indicated at 46, and rests on an annular shoulder 47 to which it is secured by pins 48. This shoulder, which extends a suitable distance upwardly from the upper end of section 30, receives the lower end of section 29 and interlocks the two sections together. The upper face of flange 46 bears against the underside of collar 17a and provides a stop to limit the upward movement of the lower casing member 28 relatively to said shaft and casing 12.

Flange 46, collar 17a, and bearing rings 24 and 26 are received in a large bore 49 formed in the lower part of section 29. This large bore connects at its upper end with a smaller bore 50 which opens into an oil chamber 51 formed in the upper portion of section 29. The smaller bore 50 receives a bushing 52 which forms a bearing for the intermediate portion of shaft 17. The lower end of this bushing is provided with a flange 53 which rests on the upper bearing ring 26 to which it is secured by screws 27. These screws are seated in apertures formed in the inwardly disposed flange 29a of section 29 by said reduced bore 50 and said screws are removable through oil chamber 51. The upper end of section 29 is provided with a bore 55 which leads upwardly from chamber 51. Arranged in this bore is a cup member 56, the flanged upper end of which rests on the upper end of section 29. The bottom wall of this cup member is provided with a central aperture through which the shaft 17 extends upwardly from chamber 51. The lower end of this cup member receives a ring 57 and the upper end is provided with a ring 58 which is channel-shaped in cross section and is provided with a flange 59 which overlies the flange of cup member 56. These flanges are provided with apertures in which are received screws 60 which are screw-seated in the upper end of section 29 and serve to hold ring 58 and cup member 56 in position. Interposed between rings 57 and 58 is a packing 61 which surrounds shaft 17 and forms a seal therefor so that oil cannot escape upwardly along said shaft from chamber 51.

Section 29 is provided with a series of obliquely disposed bosses 62 (three in the instant case) space equidistant about the axis of rotation and extending downwardly from the cup-shaped member 56. Each of these bosses is provided with a threaded bore in which is received a screw 64. This screw extends through an aperture formed in cup member 56 and bears against the obliquely disposed wall 57a of the bottom ring 57. Thus by turning said screws said ring can be adjusted upwardly to compress the packing 61 when the latter is worn.

The upper or stationary casing member 12 is formed at its lower end with a skirt 12a which overhangs and encloses the upper end of section 29 and the flanged ends of ring 58 and cup member 56. This skirt is provided near its lower end with an annular shoulder 12b. The upper end of section 29 is provided adjacent to said shoulder 12b with an upwardly presented annular shoulder 65 having a groove or annular seat 66 formed therein. Spaced below this shoulder and formed adjacent to the lower end of skirt 12a said section 29 is formed with another shoulder 67 having an 150

annular groove or seat 68. These grooves 66 and 68 are filled with grease and form a seal between section 29 and skirt 12a so that dust cannot enter. The space formed by the channel-shaped ring 58 is also filled with grease to provide lubrication for the upper portion of shaft 17 and to provide additional dust seal. The grease is forced into the chamber formed by skirt 12a through aperture 69 which is normally closed by a cap 70. The upper wall of ring 58 is provided with apertures 71 through which grease is admitted into said ring. An annular chamber 69a is formed in the lower end of casing 12 adjacent to aperture or bore 69 and above the ring 58. This chamber 69a not only serves to distribute the grease to apertures 71, but serves as a reservoir for the grease.

The lower end of bore 45 extends a suitable distance below the lower end of shaft 17 and is tapered to form an oil reservoir 74 which contains a suitable quantity of oil. The peripheral face of the lower portion of shaft 17 and of collar 17a is provided with a spiral groove or screw-thread 75 which extends upwardly to a point above the upper end of bushing 52. Thus the lower end of the groove is disposed in the oil reservoir 74 and the upper end of said groove is disposed in oil chamber 51. The arrangement of the groove 75 with respect to the direction of rotation of the lower casing member 28 is such that oil is caused to flow upwardly in the groove from reservoir 74. Thus bearings or bushings 44 and 52 as well as bearing rings 24 and 26 are provided at all times during the operation of the journal with an ample supply of lubricant.

The rotation of the casing member 28 causes the oil in chamber 51 to move upwardly upon the peripheral wall of said casing and to be deflected inwardly by the bottom wall of member 56 whereby the shaft apertures formed in said wall and in ring 57 are also constantly supplied with oil while the packing 61 prevents the passage of oil upwardly beyond said point.

The inner body portion 29a of section 29 is provided with a pair of diametrically opposed vertical ducts or passageways 76 which lead downwardly from oil chamber 51 into the large bore 49 occupied by the collar 17a and bearing rings 24 and 26. Thus the oil is conveyed from the oil chamber directly to these parts (see Figs. 5 and 6).

The surplus oil is returned from chamber 51 to reservoir 74 by means of a pair of diametrically opposed ducts or passageways 77 which are preferably arranged at right angles to ducts 76 (see Figs. 1 and 5). These ducts 77 extend to the lower end of member 31 where they communicate with ducts 78 formed in section 32. Ducts 78 open or discharge into reservoir 74. The oil is admitted into the journal through a filler opening 79 formed in the wall of section 31. This opening leads into chamber 51 and is spaced a sufficient distance above the upper end of ducts 76 and 77. Preferably this opening is formed in a bushing 80 which is screw-seated in said wall. A plug 81 is screw-seated in said bushing and closes the filler opening 79.

In the modified form shown in Figures 7 and 8 the upper end 82 of shaft 84 is not screw-threaded in the upper end of casing 12 but extends thereabove and receives an adjusting nut 85. This nut rests on casing 12 and supports the shaft.

A lock nut 86 is screw-seated on the threaded end of shaft 84 and locks the nut 85. A pin 87 may be used to prevent rotation of said lock nut relatively to the shaft. A cap 88 is attached to the upper end of casing 12 by bolts 89. This cap is

provided with a chamber 90 to receive nut 88 and with a smaller chamber 91 to receive nut 86. This chamber 91 is of the same cross-sectional contour as nut 86 so that the latter and shaft 84 are held against rotation when said cap is in place.

Cap 88 is provided with a shoulder 88a which bears against the nut 85 and takes up the end thrust of shaft 84. In the preferred form this end thrust is taken care of by the interengagement of the threaded shaft portion 16 with the threaded portion 15 of the casing member 12.

The lower section 30 of the revoluble casing member 28 is preferably provided with a plurality of annular grooves 30a which communicate with bores 78 and surround the bushing 44. The purpose of these grooves is to increase the oil capacity of the casing.

In the operation of the journal, when the spider is rotated the journal swings outwardly on trunnion shaft 10 so that the roller 37 is moved by centrifugal action against the grinding ring or bull ring of the mill. Thus revoluble motion is imparted to said roller and said casing member 28 with the shaft 17 as the axis of rotation and as a support for said roller carrying member 28.

The latter is supported on said shaft by means of collar 17a and carrying rings 24 and 26 while the lateral thrust is taken up by bushings or bearings 44 and 52.

The spiral groove 75 which may be formed either on the peripheral face of the shaft or in the inner faces of bushings 44 and 52 supplies lubricant to said bushings and forces the oil upwardly past said carrying rings 24 and 26 into the oil chamber 51. From this chamber the oil is delivered by gravity through ducts 76 to chamber 49 and the carrying rings while the surplus oil is returned to reservoir 74 by ducts 77 and 78. Thus a positive circulation of oil is insured and the bearings are forcibly supplied with oil.

A sufficient amount of oil is maintained in the journal so that the normal level of the oil is located in chamber 51 above the upper end of bushing 52. In this manner all of the bearings are submerged in oil and the various ducts as well as the groove 75 and chamber 49 are utilized as auxiliary reservoirs. The forcible circulation of oil from the reservoir to the oil chamber and thence downwardly not only furnishes the necessary amount of lubricant to the bearings but also assists in cooling the oil.

The packing 61 excludes dust from chamber 51 and the bearings located in revoluble casing 28 and at the same time it serves as a seal to prevent escape of oil from said chamber 51 along the shaft. This packing is adjustable by means of screws 64 so that said packing can be pressed upwardly against the ring 58 by the bottom ring 57 and form efficient seal at all times.

The grease contained in the chamber of ring 58 and in the annular chamber 69a forms additional dust seal for said shaft. Such grease as escapes from chamber 69a outwardly and downwardly between the upper end of revoluble casing 28 and the skirt 12a of the casing 12 is trapped in the upwardly presented annular grooves 68 140 formed in the stepped portions of member 28.

As the carrying rings 24 and 26 are subjected to wear and it is desired at all times to maintain the roller 37 in proper operative relation with respect to the bull ring, the shaft 17 is formed adjustable in member 12 whereby said shaft can be moved upwardly to compensate for the wear of said carrying rings. To adjust said shaft, cap 19 is detached from the upper end of member

12. This exposes the non-circular upper end 18 of said shaft whereby a wrench can be applied thereto and the shaft turned in the proper direction, thereby moving the threaded portion 16 of 5 the shaft in the threaded portion 15 of the casing upwardly or downwardly as desired.

When the cap is in position on member 12 it engages said non-circular portion 18 and locks the shaft against turning. However, other arrangements can be used than those herein disclosed to 10 adjust the shaft longitudinally relatively to the axis of the trunnion shaft 10.

My improved roller mill journal has large oil capacity and the bearings are positively supplied 15 with lubricant. There is a more even distribution of grease due to the annular chamber 69a and less grease leakage is encountered due to the cupped annular shoulders formed on the upper end of the revoluble casing member.

20 The axial adjustment of the shaft takes care of the wear of the carrying rings in a simple and efficient manner.

My improved journal is of sturdy construction without being excessively heavy and is constructed 25 that it can be readily assembled and disassembled.

While I have shown the preferred form of my invention, it is to be understood that various changes in the construction and arrangement of parts of my improved journal can be made without departing from the spirit of my invention.

I claim:

1. A journal for roller mills comprising in combination a stationary casing, a solid shaft screw-threaded at its upper end in said casing and projecting downwardly therefrom, a collar formed integral with said shaft near the lower end thereof, a revoluble casing enclosing said collar and the projecting end of said shaft and having its upper end enclosed within the lower end of 30 said stationary casing, bearings in said revoluble casing for engaging said collar and supporting said revoluble casing, the latter being provided with an oil reservoir, said shaft and said collar being provided with spiral grooves for conveying 35 oil from said reservoir to said bearings, a packing arranged in the upper end of said revoluble casing and engaging said shaft to form a dust and oil seal therefor, and means in said revoluble casing for adjusting said packing, said means including a fixed collar carried by the upper end of said 40 revoluble casing and engaging the upper end of said packing, a loose collar arranged in said revoluble casing and engaging the lower end of said packing, and a plurality of screws extending 45 obliquely and radially into said revoluble casing and engaging said loose collar whereby by adjusting 50 said screws said packing can be compressed.

2. A journal for roller mills comprising in combination a stationary casing having an axial bore, 55 the upper end of which is provided with an inter-

nal screw-thread, a solid shaft having its upper end formed with an external screw-thread engaging the screw-threaded bore of said casing, said shaft extending downwardly from the latter, a collar formed integral with said shaft near the lower end thereof, a revoluble casing enclosing the projecting end of said shaft and said collar, bearings in said revoluble casing for engaging said collar and revolubly securing said revoluble casing on said shaft, a roller fixed on the lower end of said revoluble casing, the latter being provided in its lower end with an oil reservoir, said shaft and said collar being provided with peripheral grooves and said revoluble casing being provided with passageways whereby oil from said reservoir is conveyed under pressure to said bearings by said peripheral grooves and is returned by gravity to said reservoir through said passageways, a packing arranged in the upper end of said revoluble casing and engaging said shaft to form a dust and oil seal therefor, and a plurality of screws screw-seated in said casing and extending radially thereinto for engaging said packing, said screws being adjustable for adjusting the compression of said packing.

3. In a journal for roller mills, the combination with a stationary solid shaft having an integral collar formed near its lower end, of a revoluble casing enclosing the lower end of said shaft including said collar, bearings engaging said collar 105 for supporting said casing on said shaft, a roller carried by the lower end of said casing, a packing arranged in the upper end of said casing and engaging said shaft, a ring fixed to the upper end of said casing and engaging the upper end of said 110 packing, a ring movably arranged in said casing adjacent to the lower end of said packing, and a plurality of adjusting screws screw-seated radially and obliquely in said casing and engaging said movable ring whereby the latter can be adjusted 115 by said screws to increase the compression of said packing.

4. In a journal for roller mills, the combination of a stationary shaft having an integral collar near its lower end, a revoluble casing enclosing the lower half of said shaft including said collar, a roller mounted on the lower end of said casing, a fixed bearing member fixed to the upper face of said collar, a revoluble bearing member fixed to said casing and engaging said fixed bearing member whereby said casing is revolubly supported on said collar, a seal ring fixed to the upper end of said casing, another seal ring movably arranged in said casing below and in spaced-apart relationship with said fixed seal ring, a compressible packing arranged between said seal rings and engaging said shaft, and means for adjusting said movable seal ring to increase the pressure contact between said packing and said shaft.

CHARLES EDWARD HERMANN. 135
